CLAIM

The ornamental design for a frame for a microwell plate assembly, as shown and described.

DESCRIPTION

FIG. 1 is a first perspective view of a first embodiment of a frame for a microwell plate assembly;

FIG. 2 is a top view of the frame for a microwell plate assembly.

FIG. 3 is a bottom view of the frame for a microwell plate assembly.

FIG. 4 is a side view of the frame for a microwell plate assembly.

FIG. 5 is another side view of the frame for a microwell plate assembly.

FIG. 6 is a front view of the frame for a microwell plate assembly.

FIG. 7 is a back view of the frame for a microwell plate assembly.

FIG. 8 is a top perspective view of the frame mounted in a microwell plate assembly.

FIG. 9 is an exploded and partially rotated perspective view of the frame and microwell plate assembly of FIG. 8.

FIG. 10 is a top perspective view of a second embodiment of a frame for a microwell plate assembly.

FIG. 11 is a top view of the frame for a microwell plate assembly of FIG. 10.

FIG. 12 is a bottom view of the frame for a microwell plate assembly of FIG. 10.

FIG. 13 is a side view of the frame for a microwell plate assembly of FIG. 10.

FIG. 14 is another side view of the frame for a microwell plate assembly of FIG. 10.

FIG. 15 is a front view of the frame for a microwell plate assembly of FIG. 10.

FIG. 16 is a back view of the frame for a microwell plate assembly of FIG. 10.

FIG. 17 is a top perspective view of the frame of FIG. 10 mounted in a microwell plate assembly; and,

FIG. 18 is an exploded and partially rotated perspective view of the frame and microwell plate assembly of FIG. 17.

The dashed lines in the figures depict portions of the frame for a microwell plate assembly that form no part of the claimed design.
